UNITED STATES PATENT OFFICE.

WILLIAM P. A. MACFARLANE, OF CHICAGO, ILLINOIS, ASSIGNOR TO
RICHARD FITZGERALD, OF CHICAGO, ILLINOIS.

FLUID-PRESSURE BRAKE.

No. 807,087.

Specification of Letters Patent.

Patented Dec. 12, 1905.

Application filed July 18, 1905. Serial No. 270,216.

To all whom it may concern:

Be it known that I, WILLIAM P. A. MACFARLANE, a citizen of the United States, residing at Chicago, in the county of Cook and State of Illinois, have invented certain new and useful Improvements in Fluid-Pressure Brakes, of which the following is a specification.

My invention relates to fluid - pressure brakes, and more particularly to means operating in connection with and controlling the so-called "triple-valve device," or rather the service mechanism thereof, for the purpose of braking the car according to its empty and loaded weight, with the result that the car may be braked with an increased pressure when loaded. In the present instance, and as hereinafter described, my invention is arranged to form a part of the so-called "triple-valve device" and to be arranged in substantially the same casing as the latter.

In the drawings, Figure 1 is a central sectional elevation of a triple-valve device embodying my invention; Fig. 2, a sectional plan taken on the line 2 of Fig. 1 with a portion thereof broken away to expose parts beneath, and Fig. 3 a detail illustrating the running of some of the ports and passages.

In the present instance I have shown my invention applied to my form of triple valve in which the brake-release mechanism, the service mechanism, and the emergency mechanism are separate and independent both physically and operatively; but it will be understood that I do not limit my invention to any specific form or character of apparatus, but contemplate using the same wherever applicable. Inasmuch as the three mechanisms just referred to do not constitute *per se* any part of my present invention, the same will be described in a more or less general manner, but sufficient for a proper understanding of the construction and mode of operation of the new parts constituting my improvements or invention.

The triple-valve device herein shown comprises a main valve body or casing 1, having secured thereto in suitable manner the top cap 2, bottom cap 3, and supplemental casing 4, this structure having suitable connections with the train-pipe, auxiliary reservoir, and brake-cylinder at the points, respectively, marked T P for train-pipe, A R for auxiliary reservoir, and B C for brake-cylinder.

Referring first to the emergency-valve mechanism, which is contained within the supplemental casing 4, such casing has an end cap 5, which closes the outer end of a chamber in which the emergency-valve piston 6 travels. Upon the outer end of the rod 6^a of this piston is arranged the emergency-valve 7, which is in the form of a puppet-valve adapted to seat upon the seat 8 and to thereby normally close the port 9 through such seat. The piston-rod passes through a partition 10, but does not fit tightly therein, thereby providing a leakage or restricted feed from the train-pipe into that part marked 11 of the piston-chamber formed on the right-hand side, Fig. 1, of the emergency-piston, that part of the piston-chamber on the other side of the piston being for convenience indicated by the reference character 12. The train-pipe air passes from the train-pipe through the connection marked T P and through the passage marked 13 in the supplemental casing, past the emergency-valve and feeds freely and without obstruction to the chamber 12 through the large passage 14 near the upper end of such supplemental casing. If desired, a light spring 15 may be employed on the outer side of the emergency-piston to assist in seating the emergency-valve after an emergency action. Upon the train-pipe reduction suitable for emergency action the pressure in the chamber 12 is suddenly reduced; but the pressure in chamber 11, not being able to leak back into the train-pipe sufficiently fast, expands in such latter chamber, thereby forcing the emergency-piston outwardly and lifting the emergency-valve off its seat, so that the train-pipe pressure is vented from the train-pipe directly to the brake-cylinder through the rather large and direct passage 16, extending transversely of the valve-body. The reservoir-pressure is also admitted in emergency action on top of the train-pipe air thus vented to the brake-cylinder in a manner hereinafter explained. This direct and transverse passage 16 is provided with a check-valve 17, normally held to its seat by the coiled spring 18.

The brake-release mechanism and the service mechanism are each operated and under the control of separate and independent diaphragms 19 and 20, respectively, which are clamped to the valve-body by the caps 2 and 3, respectively, the diaphragm 19 being clamped directly by its cap and the diaphragm

20 indirectly in the manner hereinafter explained.

Referring first to the brake-release mechanism, the brake-release valve (marked 21) is arranged to operate in a chamber 22 in the valve-body and to govern a brake-release port 23, leading to the atmosphere, such passage being formed adjacent to the release-valve in a seat or block 24, as clearly indicated in Fig.

1. The release-valve is arranged to govern the release of pressure from the brake-cylinder through the transverse passage 16 and passage 25, connecting between the transverse passage, chamber 22, and release port or passage 23. The train-pipe air is fed to the auxiliary reservoir and to the brake-release mechanism first through a common passage 31 and thence by separate passages 33 and 34, leading, respectively, to the auxiliary reservoir and to the under side of the diaphragm 19. The passage 33 continues as a passage 35 through the top cap 2, past a check-valve 44, and through a restricted port 46, thence through passages 37 and 38 to the auxiliary reservoir. A short passage 39 leads from passage 37 to the upper side of the diaphragm 19, so that the latter is always exposed on its upper face to reservoir-air and on its lower face to train-pipe air.

2. Referring next to the service-valve mechanism as herein shown, the diaphragm 20 carries a service-valve 48, arranged to work in a chamber 49, interposed between the port 50 and a passage 57, leading from the reservoir through the valve-body to the chamber on the upper side of the diaphragm 20. The port 50 communicates with the brake-cylinder through the connecting-passage 52 and the direct transverse passage 16. If desired, a light spring 55 may be employed to normally press the service-valve to its seat. The upper side of the diaphragm 20 is thus constantly exposed to auxiliary-reservoir pressure through the passage 57, while the lower side thereof is exposed to train-pipe pressure through the passage 56 leading from the train-pipe, or rather from the passage 13, directly connecting therewith, through the lower portion of the valve-body 1 and upper portion of the casing 60, hereinafter described. It will be understood that upon a reduction of train-pipe pressure for the service application of the brakes the reservoir-pressure will force the diaphragm 20 downward, and thereby open the service-valve, and thereby permitting the auxiliary-reservoir pressure to flow from the passage 57 through the chamber 49 and ports and passages 50 and 51 and 16 to the brake-cylinder.

3. The triple valve as so far described is the same as heretofore made by me, and it is in connection with such triple valve, and particularly with the service mechanism thereof, that my invention in its present embodiment is arranged to coöperate. My invention com-

prises means for preventing under certain conditions the admission of excess pressure into the brake-cylinder, or a pressure in excess of a predetermined amount, so that the wheels of the car cannot be slid by any excess pressure admitted to the brake-cylinder when the car is empty, and such means as herein shown are also arranged to permit the full pressure to be admitted into the brake-cylinder when the car is loaded. Furthermore, such means which are arranged to be manually set to a loaded-car position are adapted to be automatically returned to empty-car position whenever the car is set out from the train and is no longer in communication with the air-drum on a locomotive.

Referring to the present embodiment of my invention as herein shown, I provide means for interfering with and preventing the operation of the service-valve when the brake-cylinder pressure reaches a predetermined amount, with the result that after such degree of pressure has been admitted into the brake-cylinder the service-valve is held closed, and thereby prevented from admitting any more pressure to the brake-cylinder, notwithstanding further reductions of train-pipe pressure, and I also provide an arrangement for rendering such means inoperative at the will of the operator, so that the full pressure may be utilized for loaded-car braking.

As herein shown, I interpose between the bottom face of the main valve-body 1 and the bottom cap 3 a substantially cylindrical casting 60, which by preference serves to directly clamp the diaphragm 20 of the service mechanism in place. This casting 60 is provided with a chamber 60^a, in which is arranged a movable abutment, in the present instance a diaphragm 61, which is clamped to such casting directly by the bottom cap 3. This diaphragm 61 carries a central stem or plunger 62, which projects upwardly through a stuffing-box 63 to a position in proximity to the diaphragm 20 of the service mechanism. Normally, however, this plunger is positioned at such a distance from the latter diaphragm as to permit the same to operate freely and to thereby admit reservoir-pressure to the brake-cylinder without any interference; but the arrangement is such that upon an excess of pressure in the brake-cylinder the plunger is moved upwardly and against the diaphragm 20, or rather against the nut 64, which holds the service-valve to its diaphragm. The result of this interposition of the plunger 62 into the path of movement of the diaphragm 20 is to prevent the operation of the service mechanism and to keep the service-valve upon its seat regardless of further train-pipe reductions. To cause excess pressure in the brake-cylinder to operate the extra diaphragm 61 and move it upwardly in the manner just explained, the lower face thereof is exposed to brake-cylinder pressure through the passage 130

65, leading from the transverse passage 16 downwardly through the valve-body 1, and through the bottom cap 43 to the under side of the diaphragm 61, as clearly indicated in 5 Fig. 1, it being understood, as hereinafter explained, that the interior of the casing 60—that is, the chamber 60^a on the upper side of the diaphragm 61—is normally at atmospheric pressure. The diaphragm 61 is loaded or 10 normally pressed downwardly to the position shown in Fig. 1 by means of a spring 66 abutting at its lower end preferably upon a circular saddle 67, resting directly upon the diaphragm 61 to prevent wear thereof, and 15 at its upper end against an adjusting-ring or spring-seat 68, which is screw-threaded upon that portion of the casing 60 which forms the stuffing-box. This spring represents or corresponds to the predetermined pressure which 20 is to be admitted to the brake-cylinder for braking an empty car, and it serves to resist that pressure from the brake-cylinder which, when the brakes are applied, is pressing upwardly on the extra diaphragm 61. When, 25 however, the pressure exceeds this predetermined amount, the diaphragm 61 is forced upwardly by the brake-cylinder pressure against the tension of its spring 66, and the service-valve thereby held closed and prevented from 30 admitting additional pressure to the brake-cylinder. It is obvious that upon adjusting the ring 68 up or down the tension of the spring 66, and consequently the degree of the predetermined pressure admitted to the brake- 35 cylinder, can be varied according to the direction of adjustment of the ring.

In order to adapt the car for loaded-car braking, which is herein accomplished by throwing this special mechanism out of action, 40 I provide a transverse bore or passage through the casing 60 at one side thereof and counter-bore such passage in order to provide a larger chamber 69 and a smaller chamber 70, the remainder 71 of such passage being of sufficient 45 diameter to freely receive a rod or plunger 72, as clearly indicated in Fig. 2. The outer end of the chamber 69 is arranged to communicate with the auxiliary reservoir through the usual passage 57, leading to the upper side 50 of the diaphragm 20 of the service mechanism, and through a branch passage 73, leading from the passage 57, which passage 73 extends from the valve-body through the casing 60 and through a portion of the small cap 60^b 55 and then upwardly through a seat 74, arranged in the bottom of the chamber 69, where it emerges or terminates as a port 75. Auxiliary-reservoir pressure is therefore always present in the passage 73 and at the port 75; 60 but the flow of such pressure to the chamber 69 is prevented by the valve 76, which is carried on the inner end of the rod or plunger 72. This plunger is spring-pressed toward the valve-seat by means of a spring 77, situated in the chamber 70, which forms the

spring case or barrel therefor. The chamber 69 is normally exposed to atmospheric pressure, inasmuch as the fit of the plunger 72 in the passage 71 is not a tight one, and likewise the chamber above the diaphragm 61 is 70 normally exposed to atmospheric pressure, inasmuch as the chamber (designated 60^a for convenience) is exposed to atmospheric pressure, because the same is connected with the chamber 69 by means of a cross-passage 78, 75 as indicated in Fig. 2. The outer end of the rod or plunger 72 which extends extraneous of the casing 60 is arranged to be drawn outwardly manually when it is desired to adjust the apparatus for loaded-car braking, as hereinafter described, and to this end such plunger has a pin-and-slot connection with a lever 79, pivoted intermediate its length on a fulcrum 80 on the lug or extension 81, proceeding from the casing 60, as indicated in 80 Fig. 2. In the present instance the pin-and-slot connection is obtained through the medium of a pin 82 on the rod 72 and a slot 83 in the lever 79. This lever is provided at its opposite ends with eyes 84 and 85, which are 90 similar, with the exception that they point in opposite directions, the eye 84 being connected with a rod 86, extending transversely of the car to near one side thereof, so that it may be within easy reach of the trainman, 95 and the other eye is connected with a similar rod 87, extending to the other side of the car. By these means an outward pull of either of these special rods moves the plunger 72 in the same direction—that is, outwardly. 100

Normally the device is positioned for empty-car braking, the improvements constituting my invention being in operative condition and ready to move and hold the service-valve upon its seat when the brake-cylinder pressure exceeds a predetermined amount. When, however, it is desired to set the apparatus for loaded-car braking, the trainman pulls one of the rods 86 87, with the result that the plunger 72 is drawn outwardly against the tension of the spring 77 and the circular bead or ring 88 on the upper surface of the body of the valve 76 caused to seat upon the gasket 89, arranged at one end of the chamber 69. The result of this movement of the plunger 110 72 is to open the auxiliary-reservoir port and passage 75 and to close the passage or communication to the atmosphere through the passage 71. The reservoir-pressure now flows through the chamber 69, around the valve 76, 115 through passage 78, and into the chamber 60^a, with the result that the pressure of the spring 66 upon its diaphragm 61 is augmented by the auxiliary-reservoir pressure, and such diaphragm is therefore prevented from being 120 moved upwardly by the brake-cylinder pressure, although such latter pressure may be in excess of the load or amount represented by the spring 66—that is, the predetermined degree of pressure. The diaphragm 61 and its 125

plunger 62 are therefore rendered inoperative and thrown out of action, so that they are incapable of any interference with the operation of the service mechanism, with the result that the full amount of reservoir-air that can be obtained on an equalization can be admitted to the brake-cylinder irrespective of the predetermined degree of pressure to which the apparatus has been set for empty-car braking. As is well known, the pressure of the brake system does not remain very long on a car which has been set out from a live train—that is, a train connected up with a locomotive or source of compressed air or in a car in a train which has been detached from the locomotive—inasmuch as the air soon leaks away. By reason of this fact the return of my apparatus from its manually-set position for loaded-car braking to the empty-car position is automatic in character, for, as will be understood from an inspection of Fig. 2, the valve 76 after being set for loaded-car braking is held to such set or shifted position by the reservoir-air against tension of the spring 77. When, however, such air has leaked off from the car or been reduced below the degree of pressure exerted by the spring 77, the valve 76 will be seated by the spring and the chamber 60^a thereupon exhausted to atmosphere through the passage 71.

It will be understood that when the device is normal—that is, in condition for empty-car braking—emergency action may be obtained without interference from the special arrangement above described, inasmuch as upon a sudden and considerable reduction of train-pipe pressure necessary for emergency action the train-pipe air will be vented to the brake-cylinder, and such pressure so admitted will be augmented by the reservoir-pressure, which is admitted by the opening of the service-valve. Inasmuch as the pressure in the train-pipe has been practically or considerably depleted or reduced, the pressure on the lower side of the diaphragm 20 has been correspondingly reduced, so that the considerable preponderance of the pressure as equalized in emergency action will prevent the plunger 42 from affecting the operation of the service-valve, so that full equalization between the reservoir and brake-cylinder can be obtained in emergency action.

By preference my improvements form a component part of the triple-valve device, and the same are compactly arranged in respect thereto; but it will be understood that the particular location and arrangement thereof are not essential and that I am not to be limited thereto except when the claims expressly require it, inasmuch as I contemplate using my invention wherever applicable regardless of particular environments and position.

I claim—

1. In a device for actuating fluid-pressure brakes, the combination with the service-valve

mechanism actuated by variations in train-pipe pressure, of means for closing the service-valve and acting to so close the valve only when the brake-cylinder pressure exceeds a predetermined maximum amount.

2. In a device for actuating fluid-pressure brakes, the combination, with the service-valve mechanism actuated by variations in train-pipe pressure, of fluid-pressure-actuated means for closing the service-valve and acting to so close the valve only when the brake-cylinder pressure exceeds a predetermined maximum amount.

3. In a device for actuating fluid-pressure brakes, the combination, with the service-valve mechanism actuated by variations in train-pipe pressure, of means under the control of the brake-cylinder pressure for closing the service-valve and acting to so close the valve only when the brake-cylinder pressure exceeds a predetermined maximum amount.

4. In a device for actuating fluid-pressure brakes, the combination with the service-valve mechanism actuated by variations in train-pipe pressure, of fluid-pressure-actuated mechanism under the control of the brake-cylinder pressure and arranged to hold the service-valve closed when the brake-cylinder pressure exceeds a predetermined maximum amount.

5. In a device for actuating fluid-pressure brakes, the combination, with the service-valve mechanism, of a movable abutment under the control of the brake-cylinder pressure and inactive during ordinary graduating action of the service-valve mechanism, said abutment having a projection arranged, when the abutment is operated by excess brake-cylinder pressure, to coöperate with the service-valve and hold the same closed when the brake-cylinder pressure exceeds a predetermined maximum amount.

6. In a device for actuating fluid-pressure brakes, the combination, with the service-valve mechanism, of a movable abutment under the control of the brake-cylinder pressure, and a stem or plunger actuated by the abutment and arranged to be projected into the path of movement of the service-valve and, when operated by excess brake-cylinder pressure, to hold such valve closed.

7. In a device for actuating fluid-pressure brakes, the combination, with the service-valve mechanism actuated by variations in train-pipe pressure, of a movable abutment normally exposed on one side to atmospheric pressure and on the other side to brake-cylinder pressure when the brakes are applied, and means operated by such abutment for controlling the action of the service-valve and arranged to close the latter only when the brake-cylinder pressure exceeds a predetermined maximum amount.

8. In a device for actuating fluid-pressure brakes, the combination, with the service-valve

mechanism actuated by variations in train-pipe pressure, of a movable abutment normally exposed on one side to atmospheric pressure and on the other side to brake-cylinder pressure when the brakes are applied, said abutment being normally held with a yielding pressure corresponding with the predetermined pressure to be permitted in the brake-cylinder, and means operated by such abutment for controlling the action of the service-valve and arranged to close the latter when the brake-cylinder pressure exceeds a predetermined amount.

9. In a device for actuating fluid-pressure brakes, the combination, with the service-valve mechanism, of a movable abutment normally exposed on one side to atmospheric pressure and on the other side to brake-cylinder pressure when the brakes are applied, a spring co-operating with the abutment and opposing the brake-cylinder pressure with a tension corresponding with the predetermined degree of pressure desired in the brake-cylinder, and means operated by such abutment for controlling the action of the service-valve and arranged to close the latter when the brake-cylinder pressure exceeds a predetermined amount.

10. In a device for actuating fluid-pressure brakes, the combination, with the service-valve mechanism, of a movable abutment normally exposed on one side to atmospheric pressure and on the other side to brake-cylinder pressure when the brakes are applied, a spring co-operating with the abutment and opposing the brake-cylinder pressure with a tension corresponding with the predetermined degree of pressure desired in the brake-cylinder, means for adjusting the tension of said spring, and means operated by such abutment for controlling the action of the service-valve and arranged to close the latter when the brake-cylinder pressure exceeds a predetermined amount.

45 11. In a device for actuating fluid-pressure brakes, the combination, with the service-valve mechanism, of a movable abutment normally exposed on one side to atmospheric pressure and on the other side to brake-cylinder pressure when the brakes are applied, a spring co-operating with the abutment and opposing the brake-cylinder pressure with a tension corresponding with the predetermined degree of pressure desired in the brake-cylinder, an adjustable spring-seat by whose adjustment the tension of the spring is regulated, and means operated by such abutment for controlling the action of the service-valve and arranged to close the latter when the brake-cylinder pressure exceeds a predetermined amount.

12. In a device for actuating fluid-pressure brakes, the combination, with the service-valve mechanism, of a diaphragm controlled by 65 brake-cylinder pressure and normally subject

to a pressure equaling a predetermined brake-cylinder pressure, and a stem carried thereby and arranged to be projected to interfere with and close the service-valve when the brake-cylinder pressure exceeds such predetermined amount.

13. In a device for actuating fluid-pressure brakes, the combination, with the service-valve mechanism, of a diaphragm controlled by brake-cylinder pressure, a spring opposing 75 the brake-cylinder pressure, and a stem carried by the diaphragm and arranged to be projected to interfere with and close the service-valve when the brake-cylinder pressure exceeds the predetermined amount represented by said spring.

14. In a device for actuating fluid-pressure brakes, the combination, with the service-valve mechanism, of a diaphragm controlled by brake-cylinder pressure, a spring opposing 85 the brake-cylinder pressure, an adjustable seat for said spring to vary the tension thereof, and a stem carried by the diaphragm and arranged to be projected to interfere with and close the service-valve when the brake-cylinder pressure exceeds the predetermined amount.

15. In a device for actuating fluid-pressure brakes, the combination, with the service-valve mechanism, of a diaphragm controlled by 95 brake-cylinder pressure, a spring opposing the brake-cylinder pressure, an adjustable seat for said spring to vary the tension thereof, a spring-seat on the diaphragm to receive the spring, and a stem carried by the diaphragm 100 and arranged to be projected to interfere with and close the service-valve when the brake-cylinder pressure exceeds the predetermined amount.

16. In a device for actuating fluid-pressure brakes, the combination, with the service-valve mechanism, of a diaphragm controlled by brake-cylinder pressure, a spring opposing 105 the brake-cylinder pressure, a stem carried by the diaphragm and arranged to be projected 110 to interfere with and close the service-valve when the brake-cylinder pressure exceeds the predetermined amount, and a stuffing-box for such stem.

17. In a valve device for actuating fluid-pressure brakes in which the service-valve mechanism is independent of the brake-release and emergency mechanisms, mechanism under the control of the brake-cylinder pressure for holding the service-valve closed when 120 the brake-cylinder pressure exceeds a predetermined amount.

18. In a valve device for actuating fluid-pressure brakes in which the service-valve mechanism is independent of the brake-release and emergency mechanisms, fluid-pressure-operated mechanism under the control of the brake-cylinder pressure for holding the service-valve closed when the brake-cylinder pressure exceeds a predetermined amount. 130

19. In a valve device for actuating fluid-pressure brakes, in which the service-valve mechanism is independent of the brake-release and emergency mechanisms, mechanism 65
 5 under the control of the brake-cylinder pressure for holding the service-valve closed when the brake-cylinder pressure exceeds a predetermined amount, said last-named mechanism being arranged to resist the brake-cylinder 70
 10 pressure, and means for varying the degree of such resistance.
20. In a device for actuating fluid-pressure brakes, the combination, with the service-valve mechanism, of mechanism under the control 15
 15 of brake-cylinder pressure for holding the service-valve closed when the brake-cylinder pressure exceeds a predetermined amount, and means for rendering said last-named mechanism inoperative at the will of the operator.
21. In a device for actuating fluid-pressure brakes, the combination, with the service-valve mechanism, of mechanism under the control 20
 20 of brake-cylinder pressure for holding the service-valve closed when the brake-cylinder pressure exceeds a predetermined amount, and manually-operated means for rendering said last-named mechanism inoperative.
22. In a device for actuating fluid-pressure brakes, the combination, with the service-valve mechanism, of mechanism under the control 25
 30 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, and means 35
 35 for admitting pressure to that side of the abutment thus exposed to atmospheric pressure for loaded-car braking.
23. In a device for actuating fluid-pressure brakes, the combination, with the service-valve mechanism, of mechanism under the control 40
 45 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, and means 40
 40 for admitting pressure to that side of the abutment thus exposed to atmospheric pressure for loaded-car braking.
24. In a device for actuating fluid-pressure brakes, the combination, with the service-valve mechanism, of mechanism under the control 50
 55 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, and means 50
 50 for admitting auxiliary-reservoir pressure to that side of the abutment thus exposed to atmospheric pressure for loaded-car braking.
25. In a device for actuating fluid-pressure brakes, the combination, with the service-valve mechanism, of mechanism under the control 60
 60 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, and means 65
 65 for closing the communication between said abutment and the atmosphere and simultaneously admitting auxiliary-reservoir pressure to the abutment to oppose the brake-cylinder pressure. 70
 70
26. In a device for actuating fluid-pressure brakes, the combination, with the service-valve mechanism, of mechanism under the control 75
 75 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, and means 80
 80 for closing the communication between said abutment and the atmosphere and simultaneously admitting auxiliary-reservoir pressure to the abutment to oppose the brake-cylinder pressure, said means comprising a valve controlling the flow of said auxiliary-reservoir pressure, and a stem connected with said valve 85
 85 for operating it. 90
 90
27. In a device for actuating fluid-pressure brakes, the combination, with the service-valve mechanism, of mechanism under the control 95
 95 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, and means 100
 100 for closing the communication between said abutment and the atmosphere and simultaneously admitting auxiliary-reservoir pressure to the abutment to oppose the brake-cylinder pressure, said means comprising a spring-pressed valve controlling the flow of said auxiliary-reservoir pressure, and a stem having 105
 105 manually-operated means for actuating the same. 110
 110
28. In a device for actuating fluid-pressure brakes, the combination, with the service-valve mechanism, of mechanism under the control 115
 115 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, said 120
 120
29. In a device for actuating fluid-pressure brakes, the combination, with the service-valve mechanism, of mechanism under the control 125
 125 of brake-cylinder pressure for holding the service-valve closed when the brake-cylinder pressure exceeds a predetermined amount, comprising a movable abutment having a stem arranged to be projected into the path of movement of the service-valve, said abutment being exposed on one side to brake-cylinder pressure and on the other side to atmospheric pressure for empty-car braking, said 125

abutment operating in a chamber and constantly exposed to brake-cylinder pressure on one side and on the other side normally exposed to atmospheric air, a valve-chamber arranged at one side of and communicating with the abutment-chamber and normally at exhaust, a valve in the valve-chamber for closing said exhaust and at the same time opening the chamber to auxiliary-reservoir air which is thereby admitted to the abutment-chamber to oppose the brake-cylinder pressure.

28. In a device for actuating fluid-pressure brakes, the combination, with the service-valve mechanism, of mechanism under the control of brake-cylinder pressure for holding the service-valve closed when the brake-cylinder exceeds a predetermined amount, comprising a movable abutment having a stem arranged to be projected into the path of movement of the service-valve, said abutment being exposed on one side to brake-cylinder pressure and on the other side to atmospheric pressure for empty-car braking, said abutment operating in a chamber and constantly exposed to brake-cylinder pressure on one side and on the other side normally exposed to atmospheric air, a valve-chamber arranged at one side of and communicating with the abutment-chamber and normally at exhaust, a spring-pressed valve in the valve-chamber for closing said exhaust and at the same time opening the chamber to auxiliary-reservoir air which is thereby admitted to the abutment-chamber to oppose the brake-cylinder pressure.

29. In a device for actuating fluid-pressure brakes, the combination, with the service-valve mechanism, of mechanism under the control of brake-cylinder pressure for holding the service-valve closed when the brake-cylinder exceeds a predetermined amount, comprising a movable abutment having a stem arranged to be projected into the path of movement of the service-valve, said abutment being exposed on one side to brake-cylinder pressure and on the other side to atmospheric pressure for empty-car braking, said abutment operating in a chamber and constantly exposed to brake-cylinder pressure on one side and on the other side normally exposed to atmospheric air, a valve-chamber arranged at one side of and communicating with the abutment-chamber and normally at exhaust, a valve in the valve-chamber for closing said exhaust and at the same time opening the chamber to auxiliary-reservoir air which is thereby admitted to the abutment-chamber to oppose the brake-cylinder pressure, a valve-stem connected with the valve, and a coiled spring surrounding the stem and tending to close the valve against the reservoir-pressure.

30. The combination of a casing containing

service, brake-release and emergency mechanisms, and means also arranged within said casing for closing communication between the auxiliary reservoir and brake-cylinder and normally inactive but arranged to act when the brake-cylinder pressure has reached a predetermined amount, regardless of the pressure in the auxiliary reservoir.

31. In a device for braking cars according to weight empty and loaded, the combination, with the triple-valve and the service-valve mechanisms thereof, of means arranged to close the service-valve when, in empty-car braking, the brake-cylinder pressure reaches a predetermined amount, and mechanism for rendering said means inoperative.

32. The combination of a casing containing service, brake-release and emergency mechanisms, the service mechanism being independent of the other mechanisms, and means also arranged in the casing for controlling the operation of the service mechanism and arranged to hold the same to a position preventing the flow of auxiliary-reservoir pressure to the brake-cylinder when the brake-cylinder pressure exceeds a predetermined amount.

33. In a device for actuating fluid-pressure brakes of the species in which the service, brake-release and emergency mechanisms are independent, physically and operatively, the combination, with the service mechanism, of means for rendering the same inoperative when the brake-cylinder pressure exceeds a predetermined amount.

34. In a valve device for actuating fluid-pressure brakes in which the service-valve is independent of the brake-release and emergency valves, means for closing the service-valve when the brake-cylinder pressure exceeds a predetermined amount.

35. In a valve device for actuating fluid-pressure brakes in which the service-valve is independent of the brake-release and emergency valves, controlling means for closing the service-valve when the brake-cylinder pressure exceeds a predetermined amount, and means for rendering said controlling means inoperative.

36. In a valve device for actuating fluid-pressure brakes in which the service-valve is independent of the brake-release and emergency valves, controlling means for closing the service-valve when the brake-cylinder pressure exceeds a predetermined amount, said controlling means being normally in operative condition, and means for rendering such controlling means inoperative at the will of the operator.

37. In a device for actuating fluid-pressure brakes, the combination, with the service-valve, of mechanism arranged to hold the service-valve closed when the brake-cylinder pressure exceeds a predetermined amount,

and means for rendering said last-named mechanism inoperative at the will of the operator.

38. In a device for actuating fluid-pressure brakes, the combination, with the service-valve mechanism, of means inactive during graduation operations of the service-valve but arranged to act to close the service-valve

when the brake-cylinder pressure reaches or exceeds a predetermined maximum amount.
